UNITED STATES PATENT OFFICE.

GEORGE TURPIN CUNNINGHAM, OF SHREVEPORT, LOUISIANA.

ACETYLENE-GAS GENERATOR.

1,232,231.

Specification of Letters Patent.

Patented July 3, 1917.

Application filed April 12, 1917. Serial No. 161,527.

To all whom it may concern:

Be it known that I, GEORGE T. CUNNINGHAM, a citizen of the United States, and a resident of Shreveport, in the parish of 5 Caddo and State of Louisiana, have invented a new and useful Improvement in Acetylene-Gas Generators, of which the following is a specification.

My invention relates to improvements in 10 acetylene gas generators and it consists in the combinations, constructions and arrangements herein described and claimed.

An object of my invention is to provide an 15 acetylene generator wherein the gas is automatically generated but which is equipped with an emergency valve operating device which will be brought into play when an abnormal pressure is generated, so as to prevent the feed of carbid to the water.

20 A further object of my invention is to provide a device of the type described in which the gas pressure which operates the automatic carbid feed is taken by a by-pass to a diaphragm disposed on the opposite 25 side of the carbid hopper from the feed valve.

A further object of my invention is to provide a feed valve for the carbid hopper which is actuated normally by the ordinary 30 fluctuations of pressure within the generator itself, but which may be actuated under abnormal pressure by the auxiliary emergency device hereinafter described.

Other objects and advantages will appear 35 in the following specification and the novel features of the invention will be particularly pointed out in the appended claims.

My invention is illustrated in the accompanying drawings, forming a part of this 40 application, in which—

Figure 1 is a side view of the device, certain parts being shown in section,

Fig. 2 is an enlarged sectional view of a portion of the upper part of the generator,

45 Fig. 3 is a section on the line 3—3 of Fig. 2.

In carrying out my invention I provide a cylindrical tank 1 preferably of sheet metal which tapers toward its top as shown at 2.

In the top of the tank is disposed a hopper 3 of the shape best shown in Fig. 2. This consists of a cylindrical device having a cone-shaped bottom and being provided with laterally extending flanges 4 which are bolted to the upper edge of the tank as 55 shown at 5. The hopper 3 has a removable cover 6 which may be opened to fill the hopper with carbid.

The lower end of the hopper has an opening which is normally closed by a valve 7. 60 The stem 8 of this valve passes through a packing gland 9, thence through a pipe 10 which is secured to the hopper and connects with the diaphragm 11 in a casing 12. On the opposite side of the diaphragm is an extension 8^x of the stem 8 which is secured to the diaphragm and which passes through a pipe 13 held by the diaphragm casing. Within the pipe 13 is a screw 14 while a spring 15 is disposed between the end of the 70 screw and a nut or collar on the stem 8^x near the diaphragm.

At the bottom of the hopper 3 is a bracket 16 having guides 16^a and 16^b for the stem 8^y. A bracket 17 supports a bell-crank-lever 18 75 having a portion which straddles the stem 8^y. Connected with the bell-crank-lever is a diaphragm 19 which is disposed in a casing 20, this diaphragm being provided with a tension spring 21 whose tension may be regulated by a screw cap 22 having a portion 22^a which engages the spring, as clearly shown in Fig. 2. The diaphragm 19 is connected to the bell-crank-lever by means of a link 23.

Secured to the exterior of the tank 1 is an 85 auxiliary cylinder or casing 24. The lower part of this cylinder is fitted with water as shown at 25. A pipe 26 extends down underneath the water and communicates with an upwardly extending pipe 27 disposed within the tank. A branch pipe 28 communicates with the interior of the pipe 10 at 29. In the upper part of the casing 24 is a filtering device 30 which communicates with the delivery pipe 31.

95 From the foregoing description of the various parts of the device the operation thereof may be readily understood:

The carbid is placed in the hopper 3 through the cover 6 as stated. Water is introduced into the tank 1 through the pipe 32, the handle 33 being moved in a position to open the valves 34 and the overflow pipe 35. The water continues to flow into the tank until the water line is reached as shown on Fig. 1. When the water begins to flow out of the pipe 35 the handle is turned into 10 the position shown in Fig. 1 closing the intake and overflow pipes. The carbid passes down by gravity past the valve 7 into the water and the gas which is generated fills the space between the top of the water and 15 the top of the tank, and also passes down the branch pipe 27 and through the pipe 28 into the pipe 10 and then acts on the dia- phragm, tending to hold valve 12 in a closed position thereby preventing the further feed 20 of the carbid. As the gas is used it passes through the pipe 26 and through the water and the filter 30 and passes out through the delivery pipe 31. When the pressure lowers to a point where the pressure of the spring 25 15 will act then the valve is opened and more carbid is fed to the water thus generating additional gas.

It will be seen that the action is automatic and that all that is necessary is to relieve 30 the pressure at the delivery pipe 31 in order to cause the generation of more gas. The screw 14 is for the purpose of regulating the pressure on the spring 15 so as to cause the opening of the valve 7 at any pre- 35 determined pressure. If by any chance the valve 7 should fail to be closed by the automatic action just explained, as, for instance, where one of the parts should break, then, of course, the carbid would feed down until 40 an excess of gas pressure was reached. Now the diaphragm 19 and the spring 21 are regulated so as to act only under abnormal pressure but they will instantly respond to such abnormal pressure. The pressure on 45 the diaphragm 19 will cause the bell-crank- lever 18 to swing into an upper position so as to hold the valve 7 closed, thus preventing the feed of more carbid and the generation of additional gas. It will be seen that the 50 parts operated by the diaphragm 19 constituted an emergency device for controlling the valve 7 under abnormal conditions.

It will be noted that the automatic action of the device under normal conditions is 55 brought about by the pressure of the gas in the by-pass 28. This obviates the necessity of passing the gas through the body of the carbid itself. The result is that the device acts with more certainty since the 60 pressure is transmitted directly to the dia- phragm chamber 12 and any variation of the pressure is instantly transmitted unop- posed, whereas if the gas were permitted to enter the carbid chamber the forcing of

the gas through the carbid itself might in 65 many cases interfere with the ready re- sponse of the valve in accordance with the change in pressures. The use of the packing gland 9 prevents the entrance of the gas from the diaphragm chamber into the hop- 70 per while permitting the free movement of the valve stem 8. On the bottom of the tank 1 is an agitator 36 which is operated by a handle 37.

I claim:—

1. An acetylene generator comprising a gas tank, a hopper carried in the top of said gas tank, a valve at the bottom of the hop- 80 per for feeding carbid, means actuated by variations of the normal gas pressure within the tank for controlling the valve and auxiliary means actuated by an abnormally high pressure for closing the valve independently of the first-named controlling means.

2. An acetylene generator comprising a gas tank, a hopper carried in the top of said gas tank, a valve at the bottom of the hop- 85 per for feeding carbid, means actuated by variations of the normal gas pressure within the tank for controlling the valve, auxiliary means actuated by an abnormally high pressure for closing the valve independently 90 of the first-named controlling means, said auxiliary means comprising a diaphragm, a diaphragm chamber for said diaphragm, said chamber communicating with the interior of said generator, and a lever disposed within the generator and having connection with said diaphragm, said lever being ar- 95 ranged to engage said valve.

3. An acetylene generator comprising a gas tank, a hopper carried in the top of said gas tank, a valve at the bottom of the hop- 100 per for feeding carbid, means actuated by variations of the normal gas pressure within the tank for controlling the valve, auxiliary means actuated by an abnormally high pressure for closing the valve independently 105 of the first-named controlling means, said auxiliary means comprising a diaphragm, a diaphragm chamber for said diaphragm, said chamber communicating with the interior of said generator, a lever disposed within the generator and having connection with said diaphragm, said lever being arranged 110 to engage said valve, and means for regu- 115 lating the pressure point at which the dia- phragm will operate the lever.

4. In an acetylene generator, a tank, a carbid hopper disposed in the top of the tank, said carbid hopper having a laterally extending flange secured to the upper edge of the tank, the bottom of said hopper being conical and being provided with an opening 120 at its lower end, a valve for closing the opening, a bracket secured to the hopper, guides carried by the bracket for guiding the valve stem, a diaphragm chamber, a 125

packing gland carried by the hopper, a portion of the valve stem of said valve extending through said packing gland and into the interior of the diaphragm chamber, a 5 by-pass extending from the top of the generator around said hopper and communicating with the interior of the diaphragm

chamber, a spring on the opposite side of said diaphragm from said packing gland for normally tending to open the valve, and an 10 emergency valve closing device for acting independently of said diaphragm at a predetermined abnormal pressure.

GEORGE TURPIN CUNNINGHAM.
